(57) **CLAIM**

The ornamental design for a push pin board illustrating a soccer field, as shown and described.

DESCRIPTION

FIG. 1 is a perspective view of my new design for a push pin board which illustrates a soccer playing field;

FIG. 2 is a top plan view thereof;

FIG. 3 is a side elevational view thereof, the opposite side being a mirror image thereof;

FIG. 4 is bottom plan view thereof; and,

FIG. 5 is an end view thereof, the opposite side being a mirror image thereof.
